UNITED STATES PATENT OFFICE

ISAAC KAPLAN, OF BROOKLINE, MASSACHUSETTS, ASSIGNOR TO KAPLAN FURNITURE COMPANY, OF CAMBRIDGE, MASSACHUSETTS, A CORPORATION OF MASSACHUSETTS

DESIGN FOR A RADIO PANEL OR SIMILAR ARTICLE

Application filed January 12, 1931. Serial No. 38,277. Term of patent 7 years.

To all whom it may concern:

Be it known that I, ISAAC KAPLAN, a citizen of the United States, and a resident of Brookline, in the county of Norfolk and State of Massachusetts, have invented a new, original, and ornamental Design for a Radio Panel or Similar Article, of which the following description in connection with the accompanying drawings is a specification.

Referring to the drawings which form a part of my application:—

Figure 1 is a front elevation of my new de-

sign for a radio panel or similar article, the panel illustrated being particularly useful as a panel for a remote control dial mechanism for radio apparatus; and

Fig. 2 is a side elevation of the device shown in Fig. 1.

I claim:

The ornamental design for a radio panel or similar article, as shown and described.

In testimony whereof, I have signed my name to this specification.

ISAAC KAPLAN.
